UNITED STATES PATENT OFFICE.

ROBERT N. MILLER, OF ALTOONA, PENNSYLVANIA.

RAILROAD-TRACK-SCALE CONSTRUCTION.

1,411,502.

Specification of Letters Patent.

Patented Apr. 4, 1922.

Application filed September 14, 1920. Serial No. 410,171.

To all whom it may concern:

Be it known that I, ROBERT N. MILLER, a citizen of the United States, and residing at Altoona, Blair County, State of Pennsylvania, have invented certain new and useful Improvements in Railroad-Track-Scale Constructions, of which the following is a specification.

This invention relates to railroad track scales and particularly to means for preventing the entrance of water, dirt, grit and other foreign matter into the vault in which the scale mechanism is located.

In a track scale construction which has been found in practice to be generally satisfactory, the scale mechanism is located in a vault which is covered by a stationary deck to protect the scale mechanism from dirt, grit, snow, ice and rain water, all of which would tend to destroy the accuracy of the scales, and to prevent the escape of heated air from the vault which, in winter time, is often provided with artificial heating means. Inasmuch as the running rails are necessarily positioned above the deck, apertures must be made therein to receive rail supporting columns, the lower ends of which are mounted on the scale mechanism and the upper ends of which engage the base of the rails, and it is desirable to provide means for preventing the entrance of water, dirt, etc. through these openings and around the rail supporting columns.

It is the object of this invention to provide improved means for preventing the entrance of such foreign matter into the vault; down drafts from above the deck into the vault prevented; and "chimney action" or the escape of heated air from the vault damped. In addition to these objects further objects of the invention are; to provide means of the character described which may be quickly and easily placed in position or removed and which will not interfere with the attachment or removal of the rail columns from above the deck; which will allow the ready inspection or cleaning of the cavity around the rail column in which the foreign matter is caught and retained; and which is simpler, more easily manufactured, less expensive, and generally more satisfactory than such means heretofore designed or suggested. The invention will be fully disclosed in the following description when taken with the accompanying drawings in which:

Figure 1 is a view showing vertical elevation in full and in quarter section of a rail supporting column and one form of protective means made in accordance with this invention;

Figure 2 is a plan view of the mechanism illustrated in figure 1 the rail securing means being omitted;

Figure 3 is a cross section of the deck plate;

Figure 4 is a section on the line 4—4 of figure 2;

Figure 5 is a plan view of a modified form of deck;

Figure 6 is a section on the line 6—6 of figure 5.

In Patent 1,257,553, issued to Axel S. Vogt, February 26, 1918, a draining system for track scales is described, and this invention comprises an improvement on the structure disclosed in the patent mentioned. In the system above mentioned means are provided for collecting and disposing of the rain-water and foreign material which enters the vault through the openings around the rail supporting columns. The present invention provides means for preventing such water and foreign material from entering the vault and is much simpler in construction, less expensive to manufacture, more accessible and easier to install and inspect than the device illustrated in the patent mentioned.

In the drawings a portion of a girder comprising a part of the scale mechanism is indicated at 10, a running rail at 11, and a rail supporting column at 12, this column having its base mounted on the girder 10 and having the rail secured to its top by suitable bolts 13 and clamping blocks 14. The stationary deck which covers the vault is indicated at 15 and this deck is provided with an aperture 16 through which the rail column 12 extends. The rail column illustrated in the drawings is circular in cross section and an annular flange 17, formed in two similar portions, secured together by bolts 18 is fastened to the upper portion of the rail column, and extends downwardly therefrom. Secured to the stationary deck by means of bolts 19 is a deck plate 20 also formed in two equal half portions, which plate may be circular and is provided with an upwardly extending flange portion 20'. The depending flange member 17 overhangs the 110

upwardly extending flange 20' and these flanges comprise a baffle preventing the entrance of rain-water and dirt into the vault, as well as hindering all drafts through the 5 opening around the rail column, either up or down, which drafts might disturb the heating of the vault and affect the accuracy of the scale mechanism.

The diameter of the opening 16 in the 10 stationary deck is such that the rail column may be easily inserted therethrough when the deck plate 20 is removed, and conveniently secured to the girder. The flange member 17 and the deck plate 20 being 15 formed in halves may be quickly applied or removed to inspect the cavity beneath the flange 17. The structure disclosed is simple, inexpensive and easy to manufacture and does away with the devices heretofore found 20 necessary for collecting the water and dirt which enter the vault. It will be understood, of course, that in a track scale construction a number of rail supporting columns and a number of the protecting devices are employed although only one rail column and protecting device is shown in the drawings.

In applying the deck plate the two halves are each bolted to the deck with the grooves 30 21 formed in the edge of one section lying parallel to the correspondingly shaped groove or recess 22 in the other portion, and the slot and grooves filled with a cement which prevents leakage of water between 35 the halves and into the vault.

In Figures 5 and 6 a deck plate is illustrated which has two apertures for rail columns instead of a single aperture and this form of deck plate is used whenever 40 two rail columns are to be placed close together. It is obvious that still other forms of deck plates may be devised and also other forms of flanges which are secured to the rail columns and that the invention is not

limited in its scope to the exact structure 45 disclosed.

Having thus described the invention what is claimed as new and desired to be secured by Letters Patent is:

1. In a track scale, the combination with 50 a scale deck having openings, of scale mechanism below the deck, running rails above the deck, rail columns carried by the scale mechanism extending through said openings and supporting said rails, and 55 means for preventing the passage of water and foreign material through the openings around the rail columns comprising a downwardly extending flange detachably secured to the rail columns and plates removably secured to the deck and having upwardly extending flanges forming baffles with said first mentioned flange and said means being readily removable to completely expose the opening around the rail column, for the purpose set forth. 60

2. In a track scale, the combination with 70 a scale deck having an opening, of scale mechanism below the deck including a girder, a running rail above the deck, a rail 75 column mounted on said girder and extending through said opening and supporting said rail, and means for preventing the passage of water and foreign material through the opening around the rail column comprising a plate secured to the deck and having an upwardly extending flange said plate being formed in sections detachably secured together, and a flange member secured to the rail column above the plate and overhanging the first mentioned flange, said flange member being also formed in sections detachably secured together, the flange member and plate being readily removable to completely expose the opening around the 80 rail column, for the purpose set forth. 85

In testimony whereof I affix my signature.
ROBERT N. MILLER.
